Primary Examiner — Kevin Rudzinski(74) *Attorney, Agent, or Firm* — Life Technologies Corporation(57) **CLAIM**

The ornamental design for a display screen with graphical user interface of a cell counter, as shown and described.

DESCRIPTION

FIG. 1 is a front view of an embodiment of a display screen with graphical user interface of a cell counter showing our new design.

FIG. 2 is a front view of a second embodiment of a display screen with graphical user interface of a cell counter showing our new design; and,

FIG. 3 is a front view of a third embodiment of a display screen with graphical user interface of a cell counter showing our new design.

The portions of the display screen, text, and other features depicted in broken lines are not part of the claimed design.

1 Claim, 3 Drawing SheetsFIG. 2

FIG. 3
